UNITED STATES PATENT OFFICE.

WILLIAM B. WALLACE, OF NORWICH, CONNECTICUT.

STOP FOR POWER-PRESSES.

SPECIFICATION forming part of Letters Patent No. 585,322, dated June 29, 1897.

Application filed October 21, 1895. Serial No. 566,444. (No model.)

To all whom it may concern:

Be it known that I, WILLIAM B. WALLACE, a citizen of the United States, residing at Norwich, in the county of New London and State 5 of Connecticut, have invented certain new and useful Improvements in Stops for Power-PresSES, which improvements are fully set forth and described in the following specification, reference being had to the accompanying sheets of drawings.

This invention consists of an attachment for that class of presses or punches in which the stock to be punched is introduced to the machine in the web or strip and is fed along 15 intermittently between the successive movements of said punch; and my object is to provide a simple, inexpensive, and effective device which shall serve as a combined stop and gage to limit the forward travel of said strip. 20 By thus controlling positively the feed movement of the strip the machine may be safely operated at a much more rapid rate than when the strip is moved and adjusted wholly by hand, as now most commonly practiced. A 25 marked saving of stock is also effected by the use of my improved device.

My said improvement is of such form that it may be readily attached to presses as now constructed.

30 To explain said invention most clearly, I have annexed hereto two sheets of drawings, in which—

Figures 1 and 2 are respectively side and front elevations of portions of a power-press 35 having my stop mechanism properly attached thereto. Fig. 3 is a plan view of a strip of material partly punched, showing the relative positions of the punch and my new stop. Fig. 4 illustrates a modified means, hereinafter explained in detail, for supporting the principal 40 shaft of my device. Figs. 5, 6, and 7 are respectively plan, rear side, and end views of my device detached from the press; and Fig. 8 illustrates the threaded portion of said principal shaft.

45 Referring to the drawings, the letter *a* indicates a hanger of bracket form, that is here shown as screwed to the head *A* of the press immediately at the rear of the vertically-reciproating carriage *B*. *b* denotes a punch secured to and movable with said carriage,

and *c* denotes a die secured to the bed of the press.

d indicates a rock-shaft which in Figs. 1, 2, 5, 6, and 7 is shown as journaled in hanger *a*. This shaft could, however, be hung on centers between pendent brackets or plates *d'*, as shown in Fig. 4, but I prefer to use the hanger *a* for the reason that it affords a more convenient means for endwise adjustment of 60 the shaft, as I shall explain. It will be noticed that said shaft *d* is supported only at one end, thus leaving the exposed portion free to receive and support other operative elements of my device. That portion of said 65 shaft that is journaled in hanger *a* is formed with right and left hand screw-threads *d*² *d*³, each of which has mounted thereon a nut *d*⁴ and check-nut *d*⁵, and it will be understood that by properly regulating said nuts the shaft 70 may be adjusted longitudinally in the hanger. Secured to said shaft by set-screw *e* is an arm *e'*, extending toward the punch *b* and having journaled in its free end a short rock-shaft *e*². One end of shaft *e*² is formed with a head *e*³, 75 whose circumferential edge is cut away or notched, as at *e*⁴ *e*⁵, and within one of said notches *e*⁴ is located a pin *f*, that is driven into the arm *e'* and serves as a stop to limit the rotary movement of shaft *e*². *e*⁶ indicates a collar secured on said shaft *e*² to prevent endwise 80 displacement of said shaft. Secured to and coiled around the projecting end of shaft *e*² is a spring *g*, whose other end is secured to a stud *g'*, driven or screwed into the arm *e'*, said 85 spring acting with a constant tendency to rock the shaft in the direction opposite to that indicated by the arrow in Fig. 7.

h denotes a spring, one of whose ends is fastened to set-screw *e* and its other end to a 90 stud or screw *a'* in the upper rear portion of the hanger *a*. This spring *h* acts by compression to draw the set-screw *e* quickly upward, and thus depress the front end of arm *e'* and its shaft *e*². It would be quite practicable when punching long blanks to dispense with spring *h* and rely upon gravity to rock the shaft *d* back to its normal position, but for nearly all classes of work I prefer to use the spring. Secured to rock-shaft *d*, near its 100 free end, is a collar *k'*, formed with an arm *k*², that extends toward the front of the press

and is drilled or slotted to receive a rod m , whose outer end is bent downward, as at m' , and preferably in a lateral direction, as at m^2 , so that the end of said rod may be brought 5 close to the punch by suitably adjusting the collar k' on shaft d . Rod m is secured in place in arm k^2 by one or more set-screws n , and by easing back said screws the rod may be adjusted outward or inward in its seat to 10 vary the position of the free end of the rod.

Referring now particularly to Figs. 1 and 2, it will be seen that the carriage B has secured to it a bar o , whose lower end is formed as a hook o' , that is so located that when the 15 carriage and punch pass downward the hook engages and rides upon the circumferential edge of the head e^3 of shaft e^2 and finally snaps into the notch e^5 . When carriage B passes upward to draw the punch from the strip of 20 metal that is being operated upon, (indicated by letter C,) the hook o' lifts the arm e' against the resisting force of spring h , thereby rocking shaft d and lifting the rod m , whose end m' has, during the punching operation, rested 25 in one of the perforations in strip C, preferably the one last punched. By reference to Fig. 3 said strip will be seen with several holes punched therein, the punch b and the end m' of rod m being also shown in their respective places. Strip C is illustrated in said 30 Fig. 3 as if traveling from right to left hand.

When the punch passes upward and is drawn out of the strip C, the end of rod m is also raised out of the hole last punched by 35 the rocking of shaft d , as above explained. As said punch and rod leave the strip C the strip is moved forward by the attendant, (in the direction of the arrow,) and as the strip starts forward shaft d and rod m are released 40 in a manner which I will proceed to explain, and spring h instantly acts to return said shaft and rod to their normal positions, as in Figs. 1, 2, and 7.

I have already explained that the upward 45 movement of carriage B causes hook o' to lift the notched head e^3 and the connected arm e' . So soon as the end m' is lifted clear of strip C the upward movement of arm e' is stopped by means of a screw p , that is tapped 50 into the upper side of arm e' and is secured in place by a check-nut p' . The upper end of said screw abuts the head of the press at the proper instant and stops the further upward movement of the arm e' . Continued 55 upward movement of the carriage and hook then results in rocking the head e^3 and shaft e^2 against the force of spring g in the direction of the arrow of Fig. 7 until the hook releases itself from said head, when the shaft 60 e^2 is rotated back to its normal position by spring g , and the arm e' and shaft d are also returned to their initial positions, as above explained, by spring h .

It should be kept in mind that the end m' 65 drops before the carriage B and punch reach their highest positions and just as the strip C is being started forward by the attendant.

The end m' thus drops either upon the uncut portion between the two holes last cut or into the last hole, and thus acts as a pawl or stop 70 that drags along until the end wall of said last hole is reached, when it serves to stop the forward movement of the strip C. It also serves as a gage to determine exactly how much stock shall be left between the 75 holes.

In practice the attendant has only to start the strip forward as the punch leaves it, and before said strip will have moved any considerable distance the stop-rod m' will descend and check the further movement of the strip. Thus it becomes unnecessary for the attendant to pay any attention to the adjustment of the strip and he is consequently able to run the press at a much higher rate of 85 speed than if it were necessary for him to calculate and adjust by hand the forward movement of the strip at each punching.

All of the operative parts of my device are 90 adjustable. The shaft d may be adjusted endwise by means of the nuts d^4 d^5 , as explained. The arms e' and k^2 may be adjusted on said shaft. The rod m may be adjusted in the arm k^2 , and the upward travel of arm e' may be governed by adjusting the screw p 95 so that its upper end may abut the rigid head of the press earlier or later, as may be desired.

The shank of hook o' is secured in carriage B by means of a set-screw o^2 , that allows said hook to be adjusted upward or downward. It is thus made both possible and easy to adjust the various operative elements of my device relatively to the punch to meet the varying 100 requirements.

Having thus described my invention, I claim--

1. In combination a fixed die and coacting punch, a rock-shaft parallel with the movement of the material to be punched, means 110 for adjusting said shaft longitudinally in its bearings, a stop-rod secured to said shaft, means for rocking said shaft to lift the free end of said stop-rod and mechanism for forcing said free end into engagement with the 115 material to be punched.

2. In a device of the character described, a spring-pressed rock-shaft, a stop-rod secured thereto, an arm connected to the rock-shaft, a spring-pressed shaft journaled in the end 120 of said arm, means for checking the movement of the rock-shaft consisting of a stud adjustably secured to the arm and means on the tool-carriage for engaging the spring-pressed shaft, as and for the purpose described.

3. In a device of the character described, a crank-hanger, a spring-pressed rock-shaft adjustably journaled therein, an arm on the shaft, a spring-pressed shaft journaled in the 130 arm, a head formed on the spring-pressed shaft having notches formed therein, a pin on the arm engaging the walls of one of the notches, an adjustable stud secured to the

arm, a hook carried by the tool-carriage for engaging the other of said notches, and an adjustable stop-rod secured on the rock-shaft, as and for the purpose described.

4. In a machine of the character described, a rock-shaft parallel with the movement of the material being worked upon, means for adjusting said shaft longitudinally in its bearings, a stop-rod on the shaft, means for oper-

ating the shaft and means for timing the movements of the shaft relative to the movements of the tool carried by the machine, substantially as described.

WILLIAM B. WALLACE.
